UNITED STATES PATENT OFFICE.

BERNHARD KARL THIES, OF COESFELD, GERMANY.

DYEING APPARATUS.

Application filed October 23, 1924. Serial No. 745,488.

To all whom it may concern:

Be it known that I, BERNHARD KARL THIES, a citizen of the German Republic, and residing at Coesfeld, in Westphalia, Prussia, Germany, have invented certain new and useful Improvements in Dyeing Apparatus (for which I have filed applications in Germany on March 30, 1921, and in Great Britain on September 18, 1924), of which the following is a specification.

For dyeing and bleaching fabrics in light tones as uniformly as possible it has already been proposed to pass the bath alternately through two co-acting dyeing apparatus. If the pump be arranged to deliver directly to the dyeing apparatus, a certain quantity of the bath is always put in motion and it is not possible, when the dyeing apparatus are used differently, to obtain the necessary equalization of the bath, that is, a uniform and thorough mixing of the dye bath and in consequence an equal uniform dyeing of the goods. In addition to this it is difficult to obtain the necessary uniform mixture for dyeing light, one-coloured goods.

According to the present invention auxiliary vacuum vessels are used in conjunction with two co-acting dyeing apparatus, more particularly for dyeing with a circulating bath, which vessels contain the requisite reserve quantity of bath for maintaining the equalization of the bath and the contents of which are drawn into the mixing circulation between the two dyeing apparatus by the outflow pipe of each dye vat acting as an ejector on the contents of the corresponding auxiliary vacuum vessel and carrying it along to the auxiliary vacuum vessel of the other dye vat. The ejector action causes a thorough mixing and an additional mixing is effected at the entrance into the auxiliary vacuum vessel of the other dye vat. This will cause the colour to be perfectly uniform and it is possible to dye large quantities of goods without faults.

For obtaining the ejector action, the outflow pipes from the two dyeing vats are each passed through an auxiliary vacuum vessel into pipes of a larger diameter, the outflow pipes being unsupported within the larger pipes and having their ends open.

The outer pipes are connected each at the back to the corresponding auxiliary vacuum vessel and lead in opposite directions, that is, in the direction of flow, through connecting pipes of a smaller diameter each to the

auxiliary vacuum vessel of the other dyeing apparatus. If a stop-cock be provided in an upper vacuum equalizing pipe of the two auxiliary vacuum vessels and a stop-cock in each of the lower connecting pipes between the two auxiliary vacuum vessels, it is possible, when treating small quantities of goods, to use each side of the total apparatus, consisting of the dyeing vat and the corresponding auxiliary vacuum vessel with the pump, by itself, in which case, when the stop-cock is closed, the bath can not longer flow out of the pipe of larger diameter, referred to, surrounding the orifice of the outflow pipe, from the dyeing vat into the auxiliary vacuum vessel of the other dyeing apparatus, but will flow in the opposite direction within the pipe of greater diameter and back to the auxiliary vacuum vessel, from which the bath had previously been conveyed by the pump to the dyeing vat.

By this means each side will have been closed on itself.

In the accompanying drawings a constructional example of the invention is shown,

Fig. 1 being a side elevation partly in section,

Fig. 2 a plan view and

Fig. 3 a vertical section through two auxiliary vacuum vessels.

1 and 1_a are the dyeing vats for containing the goods and 2 and 2_a are the corresponding auxiliary vacuum vessels provided with sight gauges 2' and 2'' respectively. The vessels are connected at the top by an equalizing pipe 12 (Fig. 3) containing a stop-cock 13 and are each provided with a lateral branch 14 and 14_a for establishing communication with a vacuum pipe in order, after completion of the dyeing process to create a vacuum in the auxiliary vacuum vat 2 and 2_a and in this manner draw a part of the bath from the vats 1 and 1_a into the auxiliary vacuum vessels 2 and 2_a, so that the covers of vats 1 and 1_a can be opened without overflow of a part of the bath. Two pumps 3 and 3_a deliver through delivery pipes 4 and 4_a and four-way cocks 5 and 5_a to the dyeing vats 1 and 1_a. Connecting pipes 6 and 6_a for the dyeing bath are arranged between the respective four-way cocks 5 and 5_a and the bottom of the vats 1 and 1_a. The outflow pipes from the latter are marked 7 and 7_a. The pipes 7 and 7_a and the bends 8 and 8_a lead through the corresponding auxiliary vacuum vessels 2 and

2_a and, after passing out again, open into the pipes of greater diameter 9 and 9_a, which latter pipes are connected at the back to the corresponding auxiliary vacuum vessels 2 and 2_a. The other ends of the pipes 9 and 9_a are connected to pipes 10 and 10_a of smaller diameter, which lead through stop-cocks 11 and 11_a into the other auxiliary vacuum vessels 2_a, 2.

10 The apparatus shown in the drawing is suitable for dealing with large quantities of goods. 8, 9 and 10 and 8_a, 9_a and 10_a each represent an ejector. The bath flowing through 7 and 7_a emerges at the orifice of the bend 8, 8_a, and carries the bath along with it from the auxiliary vacuum vessel 2, 2_a behind it, while mixing with it, and carries the mixture through 10, 10_a into the other auxiliary vacuum vessel 2_a, 2.

15 20 It has been found in practical operation that it is impossible to obtain exactly identical shades, when dyeing is effected successively under use of the same or newly prepared baths. Through the combination of 25 the two dyeing apparatuses it is possible to dye simultaneously a large quantity of goods with eight racks, the bath being thoroughly mixed through the good circulation, through the passage of the bath 30 through the auxiliary vessel and by the two ejectors and, in consequence, an entirely uniform dye being obtained.

35 To dye large quantities, with eight racks at the same time, it is possible to build a large plant which would be economical only if at all times large quantities are to be dyed 40 the same color. In order to be able to utilize the plant also for smaller quantities, such as four racks, without great loss of bath, the combination plant is built, which permits of economical operation in the dyeing of large as well as small quantities of goods.

45 When small quantities are to be dealt with 50 each side is closed on itself, by closing the stop-cocks 13, 11_a and 11. Thus, for instance, if only the left-hand system is working the bath will flow from the pump 3 through 4 and 5 and 6 to the dyeing vat 1 and through 7 to the bend 8 and will emerge 55 from the orifice of the latter, it cannot carry any bath along with it, but will turn back and flow around the end of the bend 8 through the space between the end of the 60 bend and the pipe 9 of larger diameter to the auxiliary vacuum vessel 2 and from the latter back to the pump and so one. Perforated plates 15 and 15_a in the auxiliary vacuum vessels have an equalizing action 65 and prevent surging.

Thumb screws 16 (see Fig. 2) are provided for effecting tight closing of the flanged covers of the dyeing vats 1 and 1_a.

70 In order to prevent the formation of air pockets in the vats 1 and 1_a and facilitate a uniform dyeing of the whole of the goods, air releasing devices 17 are mounted on the covers of the vats 1 and 1_a and at the beginning of the circulation these air releasing devices 17 are open so that the air completely escapes and the dyeing apparatus is filled wholly with dyeing liquor.

What I claim is:

1. Dyeing apparatus of the character described including two dye vats, two auxiliary vacuum vessels, one of said vessels being directly connected with each of said vats, means for causing dye to pass from each of said vessels into its associated vat, an outflow pipe leading from each vat into the vessel associated with the other vat, and means for enabling dye that is passing through one of said outflow pipes to take with it by ejector action a further supply of dye from its own vacuum vessel into the other vacuum vessel.

2. Dyeing apparatus of the character described including two dye vats, two auxiliary vacuum vessels, one of said vessels being directly connected with each of said vats, means for causing dye to pass from each of said vessels into its associated vat, an outflow pipe leading out of each vat, a pipe of larger diameter than said outflow pipes leading out of each vessel, a pipe leading from the outer end of each of said larger pipes into the other vessel, each of the outflow pipes from the vat passing through the vessel associated with its own vat and terminating within the pipe of larger diameter connected therewith.

3. Dyeing apparatus as claimed in claim 1, further comprising an equalizing pipe connecting the two vacuum vessels with one another at the top, means for closing said equalizing pipe, and means for diverting at will the dye in an outflow pipe into the vessel associated with the vat from which it has just issued.

4. Dyeing apparatus as claimed in claim 2, further comprising an equalizing pipe connecting the two vacuum vessels with one another at the top, means for closing said equalizing pipe, and means for closing the pipes leading away from the outer ends of the pipes of larger diameter.

In testimony whereof I have signed my name to this specification.

BERNHARD KARL THIES.
